UNITED STATES PATENT OFFICE.

ALBERT J. MATTER, OF PORTLAND, OREGON, ASSIGNOR TO THE AMERICAN SALVAGE COMPANY, OF NEW YORK, N. Y.

SUBMARINE SALVAGE VESSEL.

1,321,383.

Specification of Letters Patent.

Patented Nov. 11, 1919.

Application filed October 16, 1916. Serial No. 125,770.

To all whom it may concern:

Be it known that I, ALBERT J. MATTER, a citizen of the United States, residing at Portland, in the county of Multnomah and 5 State of Oregon, have invented certain new and useful Improvements in Submarine Salvage Vessels, of which the following is a specification.

This invention relates to improvements in 10 submarine salvage vessels and has for its object to provide a vessel of this character, adapted to be lowered by its own propellers, to the side of the submerged wreck of a steel vessel so that it may attach itself to the hull 15 for the purpose of fastening a number of lifting pontoons.

Another object is to provide absolute 20 safety for the occupants of a vessel of this character, by making it buoyant enough to float on the surface of the water, and providing it with means for lowering it to any desired depth. It is thus adapted to automatically bring the vessel to the surface in the event of an accident to the lowering 25 mechanism.

Still another object is to provide means for propelling a vessel of this kind over the curved or uneven surface of the steel hull.

The novel features constituting my invention 30 are herein set forth and described in detail and are fully illustrated in the accompanying drawings, in which;

Figure 1 is a front elevation of my submarine salvage vessel.

Fig. 2 is a side elevation of the vessel with 35 a section of the side shown broken away to show the interior mechanism.

Fig. 3 is a sectional plan view of the stern 40 end of the vessel, taken on the line A—A, Fig. 2.

Fig. 4 shows a sectional elevation of the vessel, on the line B—B, Fig. 2, looking forward.

Fig. 5 is a detail sectional elevation of the 45 drill and its feeding and driving mechanism, taken on the line C—C of Fig. 1.

Fig. 6 is a sectional plan view of the guiding planes, on the line D—D of Fig. 4.

Fig. 7 shows a detail sectional elevation 50 through the center of one of the propelling magnets, taken on the line E—E, Fig. 1.

Fig. 8 illustrates the adjustable view-reflect 55 or in detailed elevation.

Fig. 9 shows a sectional elevation of the

subject-matter of Fig. 8, taken on the line 55 F—F.

Fig. 10 is a plan view of the speed regulating mechanism for the bottom propellers.

Fig. 11 is a sectional elevation of the search-light controlling mechanism, the 60 view being taken on the line G—G of Fig. 1.

Fig. 12 illustrates a sectional elevation of the magnet-arm and its adjusting mechanism, taken on the line H—H, Fig. 1.

Fig. 13 is a front elevation of the magnet- 65 arm in detail.

Referring to the drawings, 1 indicates the shell or hull of the vessel, which is provided with a keel 2, side guiding planes 3, a rudder 4 and propellers 5, and 6. The shell 1 is 70 preferably made spherical so as to best withstand the great water pressure in deep-sea work. Access to the interior of the shell is secured through a manhole 7 which is provided with a water-tight cover 8. 75

As the vessel is designed to carry several operators when submerged, it is apparent that a proper air supply is necessary. To this end an air-supply tube 9 is shown with one end attached to and connected with the 80 shell, its outer end being attached to an air-supply source on a tender-ship afloat on the water's surface. If desired, other means may be employed to furnish fresh air, such for instance as is used on submarines, as 85 the vessel will not be required to remain submerged for more than a few hours at a time. Impure air may be removed and ventilation secured through a vent-tube 10 which also extends from the vessel 1 to the 90 tender-ship.

Electric light and power are furnished from the tender-ship through a feed-wire 11 which is inserted through the shell of the vessel and electrically connected with motors 12, 13 and 14, a light 15 and the search-light 16. For the purpose of regulating the electric circuit it is provided with switches as shown at 17. It is found desirable to construct the vessel light enough to permit it to 100 float on the water's surface, partly submerged so that in the event of an accident to the machinery or motive power the vessel will always rise to the surface, thus allowing the occupants to escape. It is obvious 105 now that it is necessary to provide means for lowering the vessel in the water to the desired depth and this is accomplished by

means of lowering propellers 6, which are mounted on shafts 18 rotatively held in bearings 19 having stuffing boxes 20. Spur gears 21 are mounted on the inner ends of the 5 shafts 18 and mesh with each other so that by driving one of them the other is rotated in the opposite direction, thereby obviating any tendency of the propellers to rotate the vessel. Propeller 5 is similarly mounted on 10 a rotatable shaft 21' carried in a bearing 22 which is provided with a stuffing box 23.

Motive power for the aforementioned propellers 5 and 6 is provided by a motor 14 which drives a shaft 24 rotatively carried in 15 bearings 25 and 26. A shaft 27 carried in bearings 28 and 29, is driven by shaft 24 through the medium of bevel gears 30 and 31 mounted respectively on shafts 27 and 24. The shaft 21 carries at its inner end, a friction plate 32 with which is engaged a friction roller 33, slidably mounted on shaft 27 and guided by means of a roller guide 34 which is also slidably mounted on said shaft 27, and threadedly engages a screw shaft 35 25 revolutely carried in bearings on brackets 28 and 29 and provided with a hand wheel 36 by means of which the screw shaft may be rotated so as to slide the guide 34 and roller 33 upon shaft 27 to the desired location, 30 thereby regulating the speed of the propellers 5 as required, the friction roller 33 being locked by means of feather, to the shaft 27, thus forming means for driving the friction plate 32. Similar means are provided 35 for regulating the speed of the propellers 6, and comprise a friction roller 38 and guide 39 slidably mounted upon a drive shaft 40 revolutely carried in bearings 41 and 42 and driven through the medium of a vertical shaft 43 and bevel gears 44 by the 40 aforementioned motor 14. The guide 39 is threadedly mounted upon a screw shaft 45 carried in bearing brackets 41 and 42 and connected by means of bevel gears 46 with 45 a vertical shaft 47 which is revolutely mounted in bearings 48 and provided with a hand wheel 49 by means of which the speed of propellers 6 may be regulated, the gear 21 serving as a friction plate in connection with 50 friction roller 38 with which it engages. It is obvious that any form of driving or speed regulating mechanism may be employed for driving propellers 5 and 6 but it is essential that they be regulated independently of each 55 other.

The rudder 4 is controlled by means of a hand wheel 50 carried upon a shaft 51 revolutely mounted in bearings 52 and provided with a stuffing box at 53. The shaft 60 51 carries a worm which engages a worm wheel 54 carried by the pivot shaft 55 of rudder 4 thus permitting of rotation of the rudder upon its bearings by means of the hand-wheel 50 whereby the forward course 65 of the vessel is determined.

Two guide planes 3 are mounted, one at each side, upon shafts 56 revolvably carried in bearings 57 which are provided with stuffing boxes 58. Said guiding planes 3 may be rotated so as to stand at any desired 70 angle, and as it is desirable that both be maintained at the same angle at all times, I have provided controlling means comprising, as shown, two rearwardly projecting side shafts 58a which are rotatively mounted 75 in bearings 59 and 60 and carry at each end bevel gears 61, the forward ones of which engage with similar bevel gears 62 mounted, one on each of said shafts 56. The rear bevel gears 61 are adapted to engage similar bevel 80 gears 63 carried, one at each end of a rear shaft 64 revolvably mounted in bearings 65 and provided with a hand-wheel 66 by means of which the guiding planes are controlled and operated at will. Various other means 85 may be used to control the guiding planes if desired, and they could be independently operated instead of simultaneously if so preferred.

Having described the mechanism employed for propelling and guiding my submarine salvage vessel, it is evident that the vessel which normally floats just below the surface of the water, may be propelled downward in the water to any desired depth by 90 means of the lower propellers 6 and may be moved in a horizontal direction by means of the stern propeller 5 in conjunction with the guiding planes 3 and rudder 4.

To attach the salvage vessel to the sides of 100 the sunken vessel, I have provided electromagnets of novel construction and mounting as shown at 68 and 69. In order to adapt the faces of the magnets to the curved surfaces of the sunken vessel, I have provided a swivel mounting as shown in detail in Fig. 7 in which I have designated the magnet head as 69 although 68 is of similar construction. Magnet carriages 70 are threadedly mounted upon magnet operating 105 screws 71 and 72 as shown in Figs. 1, 2 and 7, said screws being provided in pairs, with oppositely inclined threads and mounted rotatively in bearings 73 and 74 respectively. The magnet heads 68 (and 69) are flanged 110 at 76 and are each carried within a shell 77 which is flanged at 78. Bolts 79 are screwed into the flange 76 after passing freely through the flange 78, thereby providing means for limiting the outward movement of 115 the magnet head 68 (or 69) within its shell 77. Springs 80, as shown, surround each bolt 79 and provide means for yieldingly holding the magnet heads 68 (and 69) to their outward limit within the shells 77. 120 The back of each shell 77 is formed with a semi-spherical depression as at 81, adapted to engage a similar depression 82 provided in each carriage 70, and is held in place by means of a large-headed bolt 83. A neck 84 125

within the depression 82 is adapted to engage the edge of the hole 85 provided in the shell 77, thus limiting the side movement of the magnet head. A pin 86 is carried by the carriage and engages a slot 87 in the shell depression 81, thereby preventing rotary movement of the magnet head.

It is now obvious that each magnet 68 and 69 is so mounted upon its carriage 70 as to permit it to swing upon its ball and socket bearing in any direction, thus accommodating the several magnets to the varying curvature of the hull to which the salvage vessel is intended to be magnetically attached. The yieldingly held magnet heads automatically adapt themselves to inequalities in the surface of the said hull, such as indentations or slight projections. This is absolutely necessary in order that the magnets may be held in close magnetic contact with the steel hull-plates.

The functions of the screws 71 and 72 are two-fold; they provide the best form of slide and also serve to propel the magnets across the face of the salvage vessel as desired. The screws just described, are operated by means of a motor 13 which through the medium of pinion 90 and gear 91 drives a horizontal shaft 92 revolvably mounted in bearings 93 and 94 and carrying at each end a bevel gear 95 which meshes with similar bevel gears 96 mounted one on each of two shafts 97. Said shafts 97 pass through bearings and stuffing-boxes (not shown) out through the shell 1 of the vessel and carry at their outer ends, worms 98 which engage worm-wheels 99, mounted on and keyed to screws 71. The gear 91 is not keyed to the shaft 92 but is mounted upon a sleeve 100 which revolves freely upon said shaft 92. Connections between sleeve 100 and shaft 92 is secured by means of a friction clutch comprising, as shown, a female member 101 which is keyed to the sleeve 100, and a male member 102 which is feather-keyed on shaft 92 and is provided with a shifting lever 103 of common construction.

Screws 72 are similarly operated by means of a vertical shaft 105, revolvably carried in bearings 106 and 107 and carrying at each end a bevel gear 108 which meshes with a corresponding bevel-gear 109 one of which is carried on each of two shafts 110 which pass through bearings and stuffing-boxes, to the outside of the salvage vessel, where they are each provided with a worm 111. Said worms 111 engage worm wheels 112 carried upon and keyed to screws 72. Referring to Fig. 4 it will be seen that shaft 105 is provided with a sleeve 113 which carries the female member 114, of a clutch similar to the one hereinbefore described. Sleeve 113 is adapted to rotate freely upon shaft 105 and is operatively connected with sleeve 100 by means of helical gears 116 and 117. A

male clutch-member 115 is feather-keyed upon shaft 105 and adapted to be thrown in engagement with the female member 114 by means of a shifting lever 119, of common construction. In operation the motor 13 70 constantly drives the sleeves 100 and 113 and power may be imparted to either or both pairs of screws 71 and 72 by operation of levers 103 and 119.

The magnets are used to magnetically attach the salvage vessel to the wrecked vessel's hull and to propel the salvage vessel along the surface of said hull. By magnetizing magnets 68 and demagnetizing magnets 69 said magnets 69 may be moved in 80 either direction upon the screws without moving the salvage vessel. The magnets 69 may now be magnetized and magnets 68 demagnetized whereupon rotation of the screws 72 will cause the vessel to travel horizontally in either direction as desired. Thus by alternately magnetizing and demagnetizing magnets 68 and 69 and properly operating screws 72, the salvage vessel may be made to travel to right or left any distance necessary. Vertical movement may be likewise secured by rotating screws 71 instead of screws 72.

As it is one of the functions of the salvage vessel to drill holes in the sides of the 95 wrecked hull for the purpose of attaching the pontoon hooks, I have devised drilling mechanism which is fully illustrated in Fig. 5 wherein is shown a vertical cross section through the longitudinal center of the drill. 100 125 indicates a drill carried by a drill-spindle 126 which operates within a bearing 127 provided with a stuffing-box 127a. The rear end of the spindle 126 is supported within a bearing in the bracket 128 and 105 carries a worm gear 129 which is slidably mounted and feather-keyed upon the spindle as shown. A plate 130 is attached to the bearing bracket to hold the worm-wheel in place. To rotate the drill-spindle, a motor 110 is provided as at 12 which in the present instance is shown with an extension shaft 132 carried by an outboard bearing 133 which also provides a bearing for a vertical shaft 134. The shafts 133 and 134 are connected 115 by means of miter gears 135 and 136 and the upper end of the shaft 134 carries a worm 137 which meshes with worm gear 129. It is evident from the foregoing that the motor 12 drives the drill-spindle through the 120 medium of gears 135 and 136, shafts 132 and 134, worm 137 and worm-gear 129. To feed the drill into the work a feed-screw 138 is provided, being mounted in bearings in bracket 128 and provided with a hand-wheel 125 as at 139. A feed-screw block 140 is threaded to receive the screw 138 and is so mounted as to surround the spindle 126 which is provided with set-collars 141 to limit the longitudinal movement of the spindle within the 130

screw-block. Manipulation of the hand-wheel 139 will drive the drill forward into the work or cause it to recede as desired. To insert the pontoon hooks in the holes 5 made by the drill just described, a magnetic arm is provided as at 145 in Fig. 1, further illustrated in Figs. 12 and 13. The magnet arm is provided with a magnetic head 146 adapted to engage and magnetically 10 maintain a pontoon hook, being connected with the switch-board for the purpose of control, whereby the magnetic head may be magnetized or demagnetized as desired. The magnetic arm 145 is slidably 15 mounted within the head 148 of the shaft 149 which is threaded at its inner end as at 150. A gear-rack 151 is mounted upon the arm 145 and meshes with a pinion 152 carried by a shaft 153 which passes through 20 the center of the shaft 149 and is provided with a hand-wheel 154. A stuffing-box is provided at the inner end of shaft 149. Said shaft 149 is rotatably and slidably mounted in bearing 156 and 157 and is provided with 25 a stuffing-box at 158.

To slidably manipulate the magnet shaft 149, a hand-wheel 160 is mounted upon a flanged sleeve 161 which is threaded to fit the threaded portion of shaft 149. A recessed bearing-ring 162 is bolted against the end of bearing bracket 157 so that the flange of sleeve 161 may rotate within the said recess, being held against end movement by means of the bearing bracket 157 and the 35 ring 162.

From the foregoing description it is evident that by rotating the hand-wheel 160, the magnet shaft 149 may be forced to slide either in or out as desired. Likewise by operating the hand-wheel 154 the magnet arm 40 may be made to slide back and forth within the head 148. In order to turn the shaft 149, a worm-wheel 164 is feather-keyed thereon as shown, being held within a recess 45 165 within the bearing bracket 157 by means of a plate 166. A worm 167 is mounted within the bearing-bracket 157 so as to engage the worm-wheel 164 and is provided with a hand-wheel 168 by means of which 50 the worm and worm-wheel and shaft 149 may be rotated as desired.

For the purpose of observation the salvage vessel is provided with a glass-covered observation opening 170, shown in cross-section in Fig. 9. As a view through this opening would be very limited, I have provided a view-reflector 171 adapted to be set at various angles so as to reflect the view from any desired direction, through the observation opening 170. The reflector comprises a mirror mounted within a frame 172 which is hingedly attached to a circular reflector-holding ring 173^a carried by a gear ring 173 revolvably held against the frame 65 174 of the observation opening, by means of

a retaining ring 175. The ring 173 is provided upon its periphery with gear teeth adapted to engage a pinion 176 carried upon a hollow shaft 177 which extends revolvably through the wall of the vessel to the interior, where it is provided with a stuffing-box 178. A hand-wheel 179 is mounted upon the shaft 177 for the purpose of rotating the pinion 176 by means of which the reflector-holding gear-ring 173 may be rotated so as to place the reflector in the desired position. A pinion shaft 180 carrying a pinion 181 upon its outer end, and a hand-wheel 182 upon its inner end, is revolvably mounted within the hollow shaft 177. A spring 70 75 actuated plunger pin 183 is carried within a tubular arm 184 of the hand-wheel 182 so that it may engage holes 185 provided in hand-wheel 179 for the purpose of locking together the two hand-wheels just mentioned so that they may be rotated simultaneously. A gear-ring 186 is rotatively mounted in an annular recess between rings 173 and 173^a and is provided with gear teeth upon its periphery and upon its outer 80 85 face as at 187 and 188 respectively. The peripheral teeth 187 engage the pinion 181 and the teeth 188 engage a gear 190 which is mounted upon a worm shaft 191 revolvably carried in bearings on the ring 173^a in 90 such position as to dispose the worm at right angles with, and back of, a hinge-shaft 192 which carries the reflector 171. The hinge-shaft 192 carries a worm-wheel 193 which meshes with and may be rotated by the 95 worm 191. By rotating the hand-wheel 182 independently of the hand-wheel 179, the reflector 171 may be rotated upon its hinge shaft 192, to any desired angle.

A search-light is provided at 16 and is 105 connected with the electric current wires as shown in Fig. 11. The search-light is pivotally mounted in a frame 195 carried upon a rotatable, hollow shaft 196 which is provided with an inner bearing 197 and passes 110 through a stuffing-box 198. The inner end of the shaft 196 carries a worm wheel 199 which engages a worm 200 mounted in bearings 201 and provided with a hand-wheel 202 by means of which the shaft 196 and 115 the frame 195 may be rotated as desired. To rotate the globular search light upon its pivotal bearings it is provided with a segmental bevel gear 204 which meshes with a bevel pinion 205 carried upon a shaft 206 120 revolvably mounted within and passing through the tubular shaft 196. A stuffing-box is provided at 207 and a hand-wheel 208 is mounted upon shaft 206 for the purpose of rotating the search-light within its 125 frame 195.

It is understood that slight changes may be made in the specific structure shown without departing from the spirit of the invention.

What is claimed is:

1. In a submarine vessel, the combination of a plurality of pairs of screws rotatably mounted on the exterior of the vessel, a carriage on each pair of screws, a casing attached to each carriage by a swivel joint, a magnet slidably mounted in the casing, guide rods for said magnet, springs for moving said magnet outwardly from the casing and stops on the ends of said rods for limiting the outward movement of said magnet.
2. In a submarine vessel, the combination of a shaft extending through and rotatably mounted in the wall of the shell, an enlarged head at the outer end of said shaft and provided with a guideway, a member slidably mounted in said guideway, a magnetic head at one end of said member, a rack bar on said member, a pinion within said head engaging said rack bar, a second shaft within said first named shaft and to the outer end of which said pinion is attached, means within said shell for slidably moving said first named shaft through the wall of the shell, means within said shell for rotating said first named shaft and means within said shell for rotating said second named shaft independently of said first named shaft.
3. In a submarine vessel provided with a window in the wall of the vessel, the combination of a rotatable ring surrounding the window, a reflector pivotally mounted upon the ring in position to reflect the view through said window from any desired angle, and means for manipulating the reflector from within the vessel.
4. In a submarine vessel provided with a window in the wall of the vessel, the combination of a rotary member associated with the window, a mirror pivotally mounted on said rotary member, means operable from the inside of the vessel for rotating the member, and means operable from the inside of the vessel for swinging the mirror about its pivot.
5. In a submarine vessel provided with a circular window in the wall of the vessel, the combination of a rotary annular member surrounding the window, means passing through the wall of the vessel for rotating said member, a second annular member mounted on said first named annular member, a mirror pivotally mounted on said second annular member, a third annular member rotatably mounted on said first annular member, means passing through the wall of the vessel for rotating said third annular member independently of said first annular member and means associated with the pivotal mounting of said mirror and operatively connected to said third annular member whereby rotation of said third annular member causes rotation of said mirror on its pivotal mounting.
6. In a submarine vessel, the combination of a hollow shaft passing through the wall of the vessel and provided at its outer end with a frame, a search light rotatably mounted in said frame, means within the vessel for rotating said hollow shaft, a second shaft passing through said hollow shaft, a gear on the outer end of said second shaft, a gear associated with said search light and cooperating with the gear on the second shaft, and means within the vessel for rotating said second shaft to rotate said search light on the frame.

In testimony whereof I affix my signature, in presence of two witnesses.

ALBERT J. MATTER.
